UNITED STATES PATENT OFFICE

HEINRICH GERKEN, OF WANDSEK, GERMANY

PUMP

Application filed May 5, 1930, Serial No. 449,913, and in Germany May 8, 1929.

My invention relates to improvements in pumps and an object of my invention is to provide a pump which has a double acting cylinder whereby the pump can pump a 5 larger quantity of liquid than is possible with a pump which employs a single acting cylinder.

A further object of my invention is to provide a device of the type described in which 10 the piston will pump liquid on its down-stroke as well as on its upstroke.

A further object of my invention is to provide a device of the type described in which several double acting cylinders are 15 arranged one below the other, thereby largely increasing the quantity of liquid pumped, such quantity being double and treble that which can be pumped with double acting cylinders of other construction.

20 A further object of my invention is to provide a device of the type described, in which the suction and pressure valves are concentrically arranged and in which the piston rod goes through several cylinders and valve 25 groups, this piston rod carrying ordinary pump pistons without valves and being connected and secured within the body of the pistons.

A further object of my invention is to 30 provide a device of the type described which is simple and compact in construction and which is adapted to be disposed in a well which has a relatively small bore.

Other objects and advantages are that in 35 consequence of the double acting of the cylinder or cylinders the liquid flows smoothly into the discharge line so that no air chamber is required, that the column of liquid to be carried is lighter than usual in consequence of comparatively small diameter of 40 working cylinder and piston, that the liquid enters into the cylinders from the outside through a number of suction valve channels thereby distributing the offtake, that valves 45 and space between working cylinder and outer cylinder have large cross-sections, thereby enabling easy flow of liquid from several cylinders into drop pipe, that the pump rod inside of the drop pipe is guided by guide-rings having large passages through which

the liquid may flow, the guide-rings preventing any buckling of the pump rod which has to do work also on the downstroke, that no counterweights or other balancing devices are required, and that the rate of revolutions 55 per minute can be made much higher than heretofore possible, thereby bringing the revolution of the crankshaft of the working head into more advantageous relation to the revolutions of modern driving machinery. 60

The advantages mentioned above have been tested and proven to exist by actual performance under all kinds of working conditions.

My invention is illustrated in the accompanying drawing forming part of this application, in which

Fig. 1 is a vertical section through a valve casing and through a suction and pressure valve, working cylinder, outer cylinder and well casing.

Fig. 2 is a cross section at a—b of Fig. 1. (Note larger pressure passages to allow easy flow of liquid from cylinders arranged further down the well.)

Fig. 3 is a vertical section of one complete double acting cylinder.

Fig. 4 shows the arrangement of several cylinders one below the other in the well casing.

One double acting cylinder consists of: one 80 working cylinder 1, one outer cylinder 2, two valve casings 11, two groups of valves, concentrically arranged.

One group of valves consists of: one pressure valve 8 with openings 8a and with connecting pipe 16 and guiding ring 15 with openings 15a, one suction valve 7 with openings 7a, one spring 17 actuating both suction and pressure valve, two piston rod guiding pieces 13 with openings 13a, one connecting piece 12, which at the same time acts as a guiding piece for the piston rod, a single or the last of several cylinders having two such connecting pieces, one of them to connect with closed endpiece 10, one piston rod 14, one piston 9 without valve. 85 90 95

Each group of valves is guided by 15 and 8 inside of the valve casing. The piston rod is guided above and below each group of valves. Each valve casing is provided with ribs 21 100

on the outside to hold the cylinder centrically in well casing. The pump rod is guided inside of the drop pipe by rings 20 having openings 20a, these rings being placed at the required distance from each other all the length of the drop pipe.

The working of the pump is shown in Fig. 3 and is as follows: On its down stroke the piston 9 creates a vacuum which tends to draw the liquid to be pumped through the upper suction valve openings 5 and the upper suction valve 7 into the working cylinder 1. Meanwhile the upper pressure valve 8 is drawn on its seat, and rests there firmly, this action being assisted by pressure of spring 17 and by pressure of liquid when the pump has been working and liquid has been pumped into drop pipe. On the return stroke, that is the upstroke, of the piston 9, a situation is created as shown in Fig. 3 for the lower group of valves, i.e. the pressure of the liquid above the piston 9 tends to press the upper suction valve 7 firmly on its seat, opens the upper pressure valve 8 and forces the liquid through openings 7a and past pressure valve 8 into the space 3 between working and outer cylinder, where, in the case of several cylinders arranged one below the other, the stream of liquid is joined by the liquid coming from lower cylinders, partly flowing through openings 8a in pressure valve 8. In the case of the upper end of one cylinder, or of the topmost of several cylinders, the liquid passes directly into the drop pipe 4. Meanwhile the upper suction valve 7 remains firmly pressed on its seat, this action being assisted by pressure of spring 17.

The process is exactly reversed in the case of the lower group of valves. On its down stroke the piston 9 forces the liquid through lower pressure valve 8, whereas on its up stroke it draws the liquid through lower suction valve 7 into the working cylinder.

It may be pointed out that the direction of movement of both suction and pressure valve corresponds with the direction of movement of the piston rod, an obvious advantage. Further it may be pointed out that there is no connection through which pressure of liquid exerted on a pressure valve can be transmitted to any part of the suction valve in such a way as to tend to lift the suction valve off its seat.

I claim:

5. 1. A pump comprising a working cylinder, an outer cylinder, a piston and two valve casings, each valve casing containing several suction channels leading the liquid from the outside to the suction valve seat, a suction valve arranged concentrically around a pressure valve and guided by such pressure valve, which suction valve allows the liquid to flow past both sides of its seat when the liquid is being drawn into the cylinder and has openings through which the liquid flows to the

pressure valve when the liquid is being pressed by the piston, a pressure valve through which passes the piston rod and which pressure valve is equipped with two guiding pieces above and below its seat, the 70 guiding pieces having openings through which the liquid flows, several pressure channels which are connected with the space between working cylinder and outer cylinder, such space forming, within the valve casing, 75 the connection between suction and pressure channels, and a spring which actuates both suction and pressure valve.

2. A pump including two or more uniform double acting deep well cylinder aggregates 80 as defined in claim 1, with the addition of sleeve nipples connecting the respective valve casings, single piston rods guided by said nipples, said piston rods being secured in the piston bodies of each single working piston 85 and extending through all working cylinders and through all groups of valves, whereby to assist in the movement of the valves on opening and closing in the same direction as the valves are moving.

In testimony whereof I affix my signature.
HEINRICH GERKEN.
